UNITED STATES PATENT OFFICE.

HOWARD M. BARBER, OF PAWCATUCK, CONNECTICUT, ASSIGNEE TO C. B. COTTRELL & SONS COMPANY, OF WESTERLY, RHODE ISLAND, A CORPORATION OF DELAWARE.

CUTTING AND FEEDING ATTACHMENT FOR PRINTING PRESSES.

Application filed December 31, 1925, Serial No. 78,579. Renewed June 18, 1927.

Machines designed especially for cutting, feeding and printing loosely woven or light fabrics such as burlap or cotton often "choke-up" because of the tendency of the material to wrinkle. This frequently requires the machine to be stopped and the printing mechanism to be "backed up" for removing the "choke". The printing mechanism can be readily "backed-up" but it is impossible to back up the cutting mechanism. Therefore, some means must be employed whereby the printing mechanism may be disconnected from and reconnected to the cutting and feeding mechanism only when in their proper relation to each other.

The object of this invention is to provide novel means whereby the machine may be stopped at any point in its cycle and the printing mechanisms disconnected from the cutting and feeding mechanism so that the printing mechanism can be "backed-up" to remove the "choke", said means requiring the bringing back of the printing mechanism into its proper relation to the cutting and feeding mechanism before the two mechanisms can be reconnected.

This invention more particularly includes a structure in which a clutch is provided in the driving connection between the two mechanisms, which clutch is operated by a lever for disconnecting and reconnecting the two mechanisms, a lever controlling member also being provided, which member is frictionally mounted on the impression cylinder shaft of the printing mechanism and manually rotatable into position to permit the clutch operating lever to be manipulated to disconnect the two mechanisms while they are still in their proper relation to each other and requiring the two mechanisms to again be brought back into their proper relationship before the clutch operating lever can be operated to reconnect the mechanisms.

A practical embodiment of my invention is represented in the accompanying drawings, in which

Fig. 1 represents in detail side elevation a machine including a printing mechanism and a cutting and feeding mechanism.

Fig. 2 represents a detail longitudinal vertical section through the machine.

Fig. 3 represents an enlarged detail view showing the parts in the positions they as-

sume when the operating lever has been moved to disconnect the two mechanisms.

Fig. 4 represents a view of the same taken at right angles to Fig. 3.

Fig. 5 represents a detail section taken in the plane of the line V—V of Fig. 3, looking in the direction of the arrows.

The machine frame is denoted by 1.

The cutting and feeding mechanism is denoted generally by 2. The web passes between the web feeding cylinder 3 and its coacting feed rolls 4 and from thence to the cutting mechanism shown herein as a rotary member 5 and a stationary member 6 having coacting blades 7 and 8 respectively. The sheets cut from the web are fed to the printing mechanism, as, for instance, by an endless carrier 9.

The printing mechanism in the present instance comprises the impression cylinder 10, its shaft 11 and the four plate cylinders 12. This impression cylinder may be driven in the usual manner from any suitable source of power, not shown herein. The impression cylinder is provided with a gear 13 which meshes with an intermediate gear 14, which, in turn meshes with a gear 15, carried by a cross shaft 16. The driving connection between the cutting and feeding mechanism and the printing mechanisms is herein shown as including a bevel gear 17 on the cross shaft 16, which meshes with a bevel gear 18 on the lower member 19 of a clutch, the upper member 20 of which clutch is slidably keyed on a vertical shaft 21 which is provided with a bevel gear 22 which meshes with a bevel gear 23 on the longitudinally disposed shaft 24 of the cutting and feeding mechanism.

This clutch is utilized for disconnecting and reconnecting the printing mechanism from and to the cutting and feeding mechanism. The clutch operating lever is pivoted at 25, its inner arm 26 being connected to the movable clutch member 20 and its outer arm 27 being arranged to be engaged by a suitable retaining member 28 for removably holding the lever in either of its two positions with the clutch closed or opened. The means which I have shown for controlling the operation of the clutch lever comprises a rod 29, attached at its lower end at 30 to the outer arm 27 of the clutch operating lever, the upper end of said rod being bifur-

cated to slidably embrace the impression cylinder shaft 11. A hand wheel 31 is frictionally mounted upon the impression cylinder shaft 11 so that the hand wheel may be 5 manually rotated on said shaft. The hand wheel is provided with a circular flange 32 which has an opening 33 therethrough. The rod 29 of the clutch operating lever is provided with a stud 34 which is located within 10 the hand wheel flange 32 when the clutch is closed and the mechanisms are operatively connected, so that the lever cannot be operated until the hand wheel is rotatively adjusted to bring the opening 33 in the circular 15 flange 32 opposite the stud 34. A plate 35 is fastened onto the end of the cylinder shaft 11 for retaining the hand wheel 31 and rod 29 in position thereon.

A hub 36 fixed to the outer end of the 20 shaft 16 is adapted to be engaged by a bar (not shown herein) for "backing up" the printing mechanism after it has been disconnected from the feeding and cutting mechanism, for removing a choke; and for 25 returning the printing mechanism to its proper position relative to the feeding and cutting mechanism to permit its reconnection to the same.

In operation: The machine is stopped as 30 soon as a "choke" in the material is formed. The wheel 31 is then turned on the impression cylinder shaft 11 until the opening 33 is brought opposite to the stud 34. This will permit the clutch operating lever to be manipulated to open the clutch and thereby disconnect the printing mechanism from the cutting and feeding mechanism. The printing mechanism may then be "backed up" to 35 remove the choke. The printing mechanism is then returned to its original position in proper relation to the cutting and feeding mechanism, to bring the opening 33 in the flange 32 of the wheel 31 opposite the stud 34 on the rod 29 of the clutch operating 40 lever. The clutch operating lever can then be moved to close the clutch and reconnect the two mechanisms. The machine may then be started.

From the above description it will be seen 50 that I have provided means whereby the cutting and feeding mechanism can be stopped at any point in its cycle. I have also provided means whereby the printing mechanism must be brought into its proper 55 relation to the cutting and feeding mechanism before they can be reconnected, after they have been disconnected. The driving connection controlling means herein described is not only useful for the ready elimination of chokes in the material being provided but it is also useful for permitting the cutting and feeding operation to be stopped and the printing mechanism disconnected while "making ready" and mounting 60 the plates.

It is evident that various changes may be resorted to in the construction, form and arrangement of the several parts without departing from the spirit and scope of my invention; hence, I do not wish to be limited 70 to the particular embodiment herein shown and described, but

What I claim is:—

1. A printing mechanism and a cutting and feeding mechanism having a driving 75 connection, and means manually movable to permit their disconnection and reconnection only when in their proper relation to each other.

2. A printing mechanism and a cutting 80 and feeding mechanism having a driving connection, means for disconnecting and reconnecting said mechanisms, and a member manually movable to permit the operation 85 of said means only when the mechanisms are in their proper relation to each other.

3. A printing mechanism and a feeding 90 mechanism having a driving connection including a clutch, a clutch operating lever for disconnecting and reconnecting said mechanisms, and a lever controlling member 95 movable into position to permit the operation of said lever only when the mechanisms are in their proper relation to each other.

4. A printing mechanism and a cutting and feeding mechanism having a driving connection including a clutch, a clutch operating lever for disconnecting and reconnecting said mechanisms, and a lever controlling member 100 movable into position to permit the operation of said lever only when the mechanisms are in their proper relation to each other.

5. A printing mechanism and a feeding 105 mechanism having a driving connection including a clutch, said printing mechanism including the impression cylinder and its shaft, a clutch operating lever for disconnecting and reconnecting said mechanisms, and a lever controlling member 110 frictionally mounted on said cylinder shaft and manually movable into position to permit the operation of the said lever only when the mechanisms are in their proper relation to each other.

6. A printing mechanism and a cutting and feeding mechanism having a driving connection including a clutch, said printing mechanism including the impression cylinder and its shaft, a clutch operating lever for disconnecting and reconnecting said mechanisms, and a lever controlling member 115 frictionally mounted on said cylinder shaft and manually movable into position to permit the operation of the said lever only when the mechanisms are in their proper relation to each other.

7. A printing mechanism and a feeding 120 mechanism having a driving connection in-

cluding a clutch, said printing mechanism including the impression cylinder and its shaft, a clutch operating lever for disconnecting and reconnecting said mechanisms, a rod attached to said lever and slidable on said shaft, a stud on said rod, and a hand wheel frictionally mounted on said shaft and provided with an annular flange engaging said stud, said flange having an opening arranged to be brought into position to release said stud for permitting the operation of the lever only when the said mechanisms are in their proper relation to each other.

15 8. A printing mechanism and a cutting and feeding mechanism having a driving connection including a clutch, said printing

mechanism including the impression cylinder and its shaft, a clutch operating lever for disconnecting and reconnecting said mechanisms, a rod attached to said lever and slidable on said shaft, a stud on said rod, and a hand wheel frictionally mounted on said shaft and provided with an annular flange engaging said stud, said flange having an opening arranged to be brought into position to release said stud for permitting the operation of the lever only when the said mechanisms are in their proper relation to each other.

20 In testimony, that I claim the foregoing as my invention, I have signed my name this 29th day of December, 1925.

25 30 HOWARD M. BARBER.
